CARL D. BROWN, OF HOPEDALE, MASSACHUSETTS, ASSIGNOR TO DRAPER CORPORATION, OF HOPEDALE, MASSACHUSETTS, A CORPORATION OF MAINE

WARP STOP MECHANISM FOR LOOMS

Original application filed February 14, 1928, Serial No. 254,201. Divided and this application filed March 14, 1929. Serial No. 347,067.

This invention relates to warp stop mechanisms for looms and more particularly to warp stop mechanism of the transversely movable detector bar type, the present application being filed as a division of application, Serial No. 254,201, filed February 14, 1928.

In warp stop mechanism of the above mentioned type relatively fixed and movable toothed detecting bars are employed, and the movable detecting bar is given its detecting movement by an actuator operated from a going part of the loom. It is found desirable at times to disconnect the actuator from its detecting bar and it has been the general practice heretofore to detachably connect the actuator and detecting bar by a link having an open-ended slot to engage a pin on the detecting bar. This construction, however, is open to the objection that the loom attendant while piecing up warp threads or working about the stop motion is liable to accidentally detach the connection between the actuator and detecting bar, and the present invention seeks to avoid this accidental detachment by providing a lock which will afford protection against accidental disconnection and yet permit intentional disconnection of the actuator and detecting bar.

The invention and novel features thereof will best be made clear from the following description and the accompanying drawings of one good form thereof.

In the drawings:

Fig. 1 is an elevation of warp stop mechanism embodying the present invention, some of the parts being shown in section and one of the drop wires being shown as arresting a detecting bar;

Fig. 2 is a sectional side elevation with some parts omitted, showing more particularly the yieldingly mounted bar actuator connected to its detecting bar and the stop bars embracing the actuator; and

Fig. 3 is a section on the line 3-3 of Fig. 2, showing the manually operable slide in its detaching position.

As is usual in warp stop mechanism of the transversely movable detecting bar type, a bracket is secured to each side of the loom

for supporting the warp stop mechanism, and in the present instance of the invention the loom frame is provided at each side thereof with a support 1 for a bracket 2 which may be adjustably secured in place by the bolts 3.

The bracket 2 has an upstanding portion 4 to which the side member 5 of the warp stop mechanism is secured by one or more bolts 6. Extending between the side members 5 at opposite sides of the loom are the warp supports 7 of which there may be any desired number. The parts so far described are of usual construction and need no further description.

Extending between the side members 5 are the fixed toothed detecting bars 8 each of which has associated with it a transversely movable toothed detecting bar 9 which may be guided in its transverse movement of the loom by a slot formed in the fixed bar 8. Obviously, there may be any number of detecting bars appropriate to the character of the loom in use and number of warp threads.

The ends of the fixed detecting bars 8 are firmly but removably secured to the supporting brackets 5 by the clamping bars 10 having the securing bolts 11. The fixed and movable detecting bars are provided with the usual teeth adapted to receive between them a fallen drop wire 12 when the warp thread

which normally supports each drop wire breaks or becomes too slack, the arrangement being such that the back and forth movement which is imparted to the detecting bar 9 during the normal operation of the loom will be arrested by the fallen drop wire to thereby effect loom stoppage.

While different forms of mechanism may be employed for imparting the detecting movements to the transversely movable bars 9, one good practical construction to this end is disclosed in the application of which this is a division, and may be briefly described as follows:—Mounted in suitable bearings 13 of the stop motion, is a rock shaft 14 to which are secured the rockers 15, and the desired connection between the rockers and the rock shaft may be readily affected by a locking screw 16, the construction being such that as

the rock shaft is given its rocking movement,

the series of rockers (only one of which is shown in the drawings) will be rocked therewith.

As indicated more clearly in Figs. 2 and 3, each of the rockers 15 is provided with a fulcrum seat 17, one at each side of the vertical plane passing through the axis of the rocking shaft 14. Mounted upon each of the rockers 15 is a detecting bar actuator 18, each of which has two pins 19 on its lower portion adapted to be seated in the fulcrum recesses 17 of the associated rocker 15, and the actuator supporting pins 19 are normally held seated in the fulcrum recesses 17 of the associated rocker by a spring 20 connected at its upper end to the actuator 18, as by a pin 21, and at its lower end to a part 22 carried by the associated rocker. Each of the detecting bar actuators 18 is connected to its associated toothed detecting bar, and should the latter be arrested in its movement by a drop wire, its actuator 18 will likewise be arrested, while the rocker itself will continue its movement, a condition which is permitted by means of the yielding connection or spring 20 between the actuator and its supporting rocker.

Loosely mounted upon the rocker shaft 14 are the stop bar carriers 23, two at each side of the warp stop mechanism, as shown. Extending between the stop bar carriers 23 are the stop bars 24 which may be rigidly secured to the associated carriers by means of the set screws 25, and the stop bars 24 normally embrace the actuator or series of actuators 18, one bar being positioned at each side of the actuators, and, as will presently appear, yielding means are provided for holding the stop bars 24 in the described relation to the actuators.

One of the stop bars 24 has secured thereto the link 26 which is provided with a slot 27 into which the opposite or companion stop bar 24 extends.

Mounted in the slotted portion of the link 26 is a plunger 28 which is normally under the influence of a spring 29 which serves to hold the end of the plunger against the stop bar 24 in the slot of the link, with the result that the two stop bars disposed at opposite sides of the actuators 18 are held in yielding relation against the opposite sides of the actuator or actuators. The plunger 28 may be appropriately carried by a sleeve 30 which may be secured by a set screw 31 to the link 26, and bearing upon the enlarged portion 32 of the plunger is the end of a flexible sheathed wire 33, which serves to transmit longitudinal movement of the plunger to thereby call into action the stop mechanism.

The details of the stop mechanism are not herein shown, as they may be of any appropriate character, as, for instance, that disclosed in the patent to Harry A. Davis and Arthur S. Johnson, No. 1,538,625, dated May

19, 1925.

From the construction thus far described it will be apparent that should one of the detecting bar actuators be arrested in its movement, it will act through one of the stop bars 24 to arrest such stop bar, whereupon the other stop bar which is moved by the actuators will act either through the link 26 or the stop bar in the slot of the link to cause relative movement of the plunger and link to thereby move the sheathed wire 33 and effect loom stoppage, as more fully set forth in the parent application above referred to.

As above indicated, the present invention relates more particularly to means for securing and locking the actuator 18 to the transversely movable toothed detecting bar 9, so that all danger of these parts being accidentally disengaged is avoided. This mechanism may take various forms but as illustrated in the present instance of the invention, the actuator 18 is provided with a manually operable slide 34, the lower end portion of which is bifurcated, as at 35, to engage a pin 36 rigidly secured to the movable detecting bar 9, the construction being such that when the slide 34 is moved downwardly relative to the actuator upon which it is mounted, the bifurcated end 35 will engage the pin 36 and upon movement of the actuator will impart movement to the detecting bar 9.

As will be apparent from Figs. 2 and 3, the actuator 18 is provided with the pins 37 which engage the elongated slots 38 in the slide 34 and these pins are provided with enlarged overlapping heads 39 adapted to retain the slide 34 in sliding engagement with the actuator 18. When the slide 34 is moved downwardly into engagement with the pin 36 of the associated detecting bar, it is important that such connection be not accidentally disturbed by the loom attendant in piecing up or manipulating parts of the loom about the warp stop mechanism. A lock is therefore provided, in accordance with the present invention, for retaining the slide 34 in engagement with the pin 36.

The construction illustrated in the drawings to this end consists of a projection 40 provided upon the slide 34 which may be constituted as a ball or sphere held in a recess formed in the slide 34. This projection or ball is adapted to engage either one of the two openings 41, 42 formed in a strap or blade 43 which overlies the projection or ball 40 carried by the slide, and the strap is held in fixed position relative to the slide by engaging beneath the enlarged heads 39 of the pins 37. The strap 43 is appropriately formed as a leaf spring, with the result that when the slide 34 is in its upper position, as indicated in Fig. 3, and the ball 40 is engaged with the upper opening 41 in the strap, the slide will be firmly held in its inactive position, thus freeing the connection between the actuator and its associated detecting bar;

similarly, when the slide 34 is in its lowered position, as indicated in Fig. 2, to which it may be readily moved by manual effort, the ball 40 will engage the lower opening in the strap and maintain the actuator locked to its detecting bar.

From the construction described it will be apparent that accidental disconnection between the actuator and its toothed detecting bar will be prevented by the manually operable slide and lock associated therewith to hold the slide in engagement with the pin 36, and when disconnected the manually operable slide will be held by the lock in its inactive position.

The movement of the slide to and from its locking position is limited by the length of the slots in the slide, the upper one preferably as shown, in connection with the pin or pins secured to the actuator and when any one of the slides in a plural bank warp stop motion is raised to disconnect the actuator from the associated detecting bar the fact is observable by the top portion of the slide projecting above the companion slides, so that the loom attendant is at once informed of whether or not any bank of the warp stop motion is functionally inoperative.

Any suitable means may be employed for imparting to the rock shaft 14 and the rockers 15 the desired rocking movement, but in the present instance of the invention the rock shaft 14 has secured thereto an arm 44, the outer end portion of which is provided with a slot 45 which is engaged by a pin 46 connected by an arm 47 with the upper end portion 48 of an actuating member 49 which may be given its desired movement to effect actuation of the rock shaft and rockers from any suitable going portion of the loom, but as such details form no part of the present invention they are not herein further described and are, moreover, well-known in the art.

45. What is claimed is:

1. In a warp stop mechanism for looms, the combination of a series of drop wires, a transversely movable detecting bar, a detecting bar actuator, means for connecting the bar actuator and the detecting bar, a lock which operates automatically as said connecting means is moved into connecting position to prevent accidental disengagement between said connecting means and the transversely movable detecting bar, and means for effecting loom stoppage when the detecting bar is arrested by a drop wire.

2. In a warp stop mechanism for looms, the combination of a series of drop wires, a transversely movable detecting bar, a yieldingly operated detecting bar actuator, manually actuated means for detachably connecting the actuator and detecting bar, a lock operated automatically by manual actuation of the connecting means to prevent accidental

disconnection, and means for effecting loom stoppage when the detecting bar is arrested by a drop wire.

3. In a warp stop mechanism for looms, the combination of a series of drop wires, a transversely movable detecting bar, a detecting bar actuator, and means for detachably connecting the actuator and detecting bar, and a friction lock which operates automatically as the actuator and detecting bar are connected by said means to prevent accidental disconnection.

4. In a warp stop mechanism for looms, the combination of a series of drop wires, a transversely movable detecting bar, a detecting bar actuator, a member for detachably connecting the actuator and detecting bar and mounted on one of them for relative movement into and out of connecting position, and an automatically operable lock for preventing accidental movement of said member out of connecting position.

5. In a warp stop mechanism for looms, the combination of a series of drop wires, a transversely movable detecting bar, a detecting bar actuator, and means for detachably connecting the actuator and detecting bar including a slide mounted for manual sliding movement upon the actuator into and out of engagement with the detecting bar and a lock which operates automatically as the slide is manually moved into engagement with the detecting bar to prevent accidental disengagement of the slide and detecting bar.

6. In a warp stop mechanism for looms, the combination of a series of drop wires, a transversely movable detecting bar, a detecting bar actuator, means for detachably connecting the actuator and detecting bar including a member mounted for longitudinal sliding movement upon the actuator into and out of engagement with the detecting bar and a friction lock which operates automatically to lock the sliding member from accidental movement into and out of engagement with the detecting bar.

7. In a warp stop mechanism for looms, the combination of a series of drop wires, a transversely movable detecting bar having a projection through which operative movement is imparted to the bar, a detecting bar actuator, and means for detachably connecting the actuator and detecting bar including a slide mounted upon said actuator for sliding movement longitudinally along the actuator into and out of engagement with said projection.

8. In a warp stop mechanism for looms, the combination of a transversely movable detecting bar, a bar actuator, means bodily mounted on the actuator for movement relative thereto into and out of operative engagement with the detecting bar, connections between said means and the actuator for limiting the movement of said means into and out

of operative relation with the detecting bar, and a lock for holding said means in either of its two positions.

9. In a warp stop mechanism for looms, the combination of a transversely movable detecting bar, a bar actuator, a connector mounted on the actuator and movable longitudinally on the actuator into and out of operative engagement with the detecting bar, and locking means between the connector and actuator acting automatically as the connector is moved into operative engagement with the detector bar for holding the connector in operative engagement with the detecting bar.
10. In a warp stop mechanism for looms, the combination of a transversely movable detecting bar, a bar actuator, a connector constituted as a slide mounted upon the actuator for longitudinal movement relative thereto into and out of engagement with the detecting bar and having its end extending above the actuator to constitute a signal when the slide is disengaged from the detecting bar, and a lock for holding the slide in either of its two positions.

In testimony whereof, I have signed my name to this specification.

CARL D. BROWN.
